GARMENT EDGE, MORE PARTICULARLY FOR
MEN'S COATS

Arthur J. C. Harper, Chicago, Ill.

Application May 28, 1948, Serial No. 29,717

1 Claim. (Cl. 2-275)

1

This invention relates to an improved garment edge, more particularly for men's coats, and, among other objects, aims to provide improved expedients for producing same.

The edge of my present invention has marked advantages of appearance, simplicity, and economy.

The invention may be understood by reference to the following description, taken together with the accompanying drawings, of an illustrative embodiment thereof, and in which drawings:

Figure 1 is a section through parts in a preliminary stage in the production of the edge;

Figures 2 to 4 inclusive are similar views of successive steps therein;

Figure 5 is a fragmentary plan view of the parts shown in Fig. 4 after the inclusion of expedients to which the present invention is directed, and being a view taken on the line 5-5 of Fig. 6;

Figure 6 is an enlarged sectional view similar to Fig. 4, but including the expedients shown in Fig. 5 and being a section taken on the line 6-6 of Fig. 5;

Figure 7 is a sectional view on the scale of Fig. 6 showing the completed edge embodying the practice of the present invention;

Figure 8 is a view, similar to Fig. 3, preliminary to a modified practice following the present invention;

Figure 9 is a fragmentary plan view of the parts shown in Fig. 8 after the inclusion of modified expedients following the present invention, and being a view taken on the line 9-9 of Fig. 10;

Figure 10 is an enlarged sectional view somewhat similar to Fig. 8 but including the expedients shown in Fig. 9 and being a section taken on the line 10-10 of Fig. 9; and

Figure 11 is a sectional view on the scale of Fig. 10 showing the completed edge embodying the practice of the modified form of the invention.

Referring in detail to the illustrative construction shown in the drawings, I have shown a piece of outside material 11 which may be any suiting fabric and which may be superimposed on an interior coat front or canvas-like element 12 and basted thereto as at 13, the basting 13 being later removed. In accordance with the better tailoring practice the margin of the canvas-like material 12 is cut away or trimmed back leaving an overhanging edge portion 14 of the material 11.

The parts just described may be inverted and superposed on a facing outside material 15 which is usually of the same suiting fabric as the ma-

2

terial 11 and is substantially coterminous therewith. Next, the layers of outside material 11 and 15 may be machine-stitched together as at 16, the latter stitch catching the edge 14 of the material 11 and a corresponding edge 17 of the material 15, but being spaced outwardly of the edge of the canvas-like element 12.

Heretofore, in conventional practice, at or about the stage last described, it has been customary to sew the edge of the canvas-like element 12 to the suiting material 11 after which the basting stitch 13 would be removed. An objection to this practice has been that such sewing of the canvas-like element to the suiting material 11 is a difficult and delicate operation in that great care must be taken to avoid having the thread so used pass completely through the suiting material and be seen on the outer surface of the material. This is particularly true when light weight spring or summer material is being worked with.

In accordance with the present invention, the canvas-like element 12, instead of being sewn to the body of the suiting material 11, is sewn to the edge margin 14 thereof, which edge margin is finally brought to the inside of the garment edge and concealed from view. Since it is immaterial whether or not the thread so used passes completely through the concealed inner edge margin 14 of the suiting material, an easier and quicker operation ensues and one which positively insures that the stitch attaching the canvas-like element 12 to the suiting material shall be concealed from view no matter how light weight the suiting material may be.

In one practice of the present invention and as shown in Fig. 4, the outer suiting material 11 and facing suiting material 15 may be spread apart about the stitch 16 securing them together and their inner edges 14 and 17 spread apart and pressed down onto the materials respectively to enhance the sharpness of the ultimate edge. As seen in the drawings, when this is done the edge 18 of the canvas-like element 12 will lie between the suiting material 11 and its inner pressed-down edge 14.

Following the present invention, and as seen in Figs. 5 and 6, a felling or cross stitch 19 is now taken through the inner edge margin 14 of the suiting material 11 and the lapping edge 18 of the canvas-like element 12. It will be seen that the stitch 19 is free of the stitch 16 and of all other parts. It may catch the element 12 at 19a and the inner edge margin 14 at 19b.

Finally, as shown in Fig. 7, the facing mate-

rial 15 and with it its inner edge 17 may be rotated about the stitch 16 and superimposed on the canvas-like element 12 and the inner edge 14 of the outer material 11, and the parts then pressed down thus completing the garment edge having the layers of outside material portions and inner edge margins as shown. If desired, an edge finishing stitch 20 may be run by machine therealong.

In the modified practice of the invention, the preliminary step as shown in Fig. 4 may be omitted and instead the attaching of the edge 18 of the canvas-like element 12 to the inner edge 14 of the suiting material 11 may take place while the parts are still in the positions shown in Fig. 3 and shown again in Fig. 8.

At this time, in accordance with the present invention, as shown in Figs. 9 and 10 a felling or cross stitch 21 may be taken from the edge 18 of the canvas-like element 12 across the stitch 16 to the inner edge 14 of the suiting material 11, the stitch 21 being independent of the stitch 16 and not engaging the materials immediately therat but rather bridging the latter. It will be seen that the stitch 21, like the stitch 16, is free of all other parts except the canvas-like element 12 and the material inner edge 14. It may catch the element 12 at 21a and the inner edge 14 at 21b.

Finally, here again, as shown in Fig. 11, the facing material 15 and with it its inner edge 17 may be rotated about the edge 16 and superimposed on the canvas-like element 12, in this instance carrying with it the inner edge 14 of the material 11, and the parts may then be pressed down to produce substantially the same completed edge as shown in Fig. 7 which again may, if desired, be finished with an edge stitch such as shown at 20 in Fig. 7. It will be noted that the element 12 in each case is desirably flat and unfolded.

It will be understood that at some time prior to the completion of the edge the basting stitch 13 is removed and also that commonly the inner edge 17 may be trimmed off as at 22 so as to be somewhat shorter than the inner edge 14 to minimize thickening of the edge.

In either practice of the invention hereinbefore described the canvas-like coat front element 12 is finally attached only to the inner concealed

edge 14 and is unfolded and unattached to the outside portions of the suiting material thus assuring that the thread effecting this securement is completely concealed within the edge and will not show on the outer surface of the garment.

An important advantage is that it makes unnecessary the use of edge tape for attaching the canvas-like element to the materials while at the same time providing enhanced economy and a thinner and smoother edge. In each instance, only five layers of material, including the inner margins, occur in the finished edge, that is, the two material outside portions, the two inner margins, and the single interior element or coat front member.

Such changes may be made as fall within the scope of the appended claim without departing therefrom.

The invention having been described, what is here claimed is:

As an article of manufacture, a garment edge consisting of two layers of material stitched together by a first stitch and folded upon themselves and upon each other to provide outside portions and inner edge margins thereof, a single interior unfolded garment front element between said materials, and a second stitch extending from the interior element to one of the said inner edge margins, said second stitch being free of the outside portions and being free of the first mentioned stitch, whereby only the said materials are folded in said edge and the said second stitch extends directly from said interior element to an inner edge margin and is free of all other parts.

ARTHUR J. C. HARPER.
